WELL SCREEN

Virgil F. Every, Rochelle Park, N. J.

Application January 28, 1944, Serial No. 520,014

5 Claims.

(Cl. 166—5)

This invention relates to well screens and the same has particular reference to an improved well screen composed of parts adapted to interfit for retaining the same in assembled relation and which may be expeditiously assembled and installed and disassembled when required for replacing worn or damaged parts and the invention is an improvement on Letters Patent No. 2,101,537 issued December 7, 1937.

The invention has in view a well screen adapted to be constructed in various lengths which may vary from a few feet to ten feet or more in length and which may be connected in end to end relation to provide the required overall length of well screen.

The invention further comprehends a well screen which includes inwardly converging longitudinally extending bars retained in circumferentially spaced relation by means of interfitting rings or bands disposed intermediate the ends thereof and which obviates the necessity of welding or peaning the bars and bands for securing the same in assembled relation.

With the foregoing and other objects in view, reference is now made to the following specification and accompanying drawing in which is illustrated the preferred embodiment of the invention.

In the drawing:

Fig. 1 is a side view of a well screen constructed in accordance with the invention and illustrating the same partly in section so as to disclose the underlying structure.

Fig. 2 is a transverse sectional view taken approximately on the line 2—2 of Figure 1.

Fig. 3 is a fragmentary perspective view illustrating the retaining ring assembled with the screen bars.

Fig. 4 is a fragmentary perspective view of one of the retaining rings.

Fig. 5 is a fragmentary perspective view of one end of one of the screen bars.

Fig. 6 is a fragmentary perspective view of a section of one of the screen bars illustrating the notched portion for receiving the retaining ring.

Referring to the drawing by characters of reference, the well screen includes oppositely disposed tubular end members 10 and 11 each formed with a peripheral groove 12 in its outer face disposed in spaced relation to the inner end thereof and providing an annular bead 13 extending from said groove to the inner end of the end member. Disposed between and interconnected with said end members, are a plurality of longitudinally extending circumferentially spaced bars 14 hav-

ing inwardly converging opposite side faces 15 so as to provide inwardly flaring or diverging water passages 16 between adjacent bars.

The bars 14 are formed with notches 17 in their inner edges which are disposed adjacent to their opposite ends respectively and of a width to snugly receive therein the annular beads 13 of the end members 10 and 11 with the ends of the bars arranged externally of the inner end portions of said end members and with the extremities 18 of said bars which lie between the notches 17 and the ends of said bars being disposed in said peripheral grooves 12. The extremities 18 at each end of said bars are externally rabbeted as at 19 thereby forming the shoulders 20 which are spaced from the notches 17 respectively. Collars 21 are provided for each end member 10 and 11 which slidably fit thereupon and are adapted to engage in said notches 19 and to abut against said shoulders 20 so as to overlie a portion of the extremities 18 of the bars 14 to thereby retain the bars 14 and the end members 10 and 11 in interfitting notched relation.

The collars 21 are formed with chamfers 22 at the juncture of their inner ends and inner peripheries so that the same snugly engage against the shoulders 20 respectively. A coupling member 23 is provided for each end member 10 and 11 which coupling members are internally threaded throughout their extent and are adapted to threadedly engage over the threaded outer ends of the end members 10 and 11 and to be tightened against the outer end edges of the collars 21 for retaining the collars in position on the end members and said coupling members 23 providing means for threadedly coupling the well screen at its opposite ends in a pipe line.

In order to reinforce the bars 14 intermediate the end members 10 and 11 and to retain the same in circumferentially spaced relation, one or more bands 24 are provided which fit in transverse notches 26 opening through the inner edges 27 of the bars 14 at longitudinally spaced intervals to thereby dispose the inner faces of the bands 24 flush with the inner edges of the bars. One end wall 28 of each of the notches 26 is disposed in substantially right angular relation with the plane of the inner edges 27 of the bars 14 while the opposite end wall 29 of each 50 of the notches is disposed at substantially 30 degrees to the plane of the bottom wall of the notches. The opposite annular end walls 31 and 32 of each of the bands 24 are shaped to conform with the end walls 28 and 29 of the notches 55 26 so as to snugly interfit therewith and retain

the bands and the bars in assembled relation since the undercut formation of the end wall 29 of the notches 26 necessitates the bowing of the bars 14 in order to spring the same into engagement with the bands. The bands are provided with radially disposed outwardly projecting ribs 33 having outwardly converging opposite side faces 34 conforming to the inwardly converging side faces 15 of the bars 14 so that the ribs interfit between the bars and space the same in said circumferential relation. The ribs 33 extend the full width of the bands 24 and are of lesser depth than the thickness of the bars 14 so that the outer faces of the ribs are recessed inwardly of the outer faces of the bars.

What is claimed is:

1. In a well screen, oppositely disposed externally threaded cylindrical end members each having an annular groove in its outer face adjacent the inner end thereof providing an annular bead extending from said groove to the inner end of the end member, bars having beveled side walls and formed with notches adjacent their opposite ends extending inwardly from their inner edges and receiving therein the annular beads of said end members respectively with the extremities of said bars interfitting in said annular grooves disposing said bars in longitudinally extending relation between and interconnected with said end members, each of said bars having its opposite ends externally rabbeted providing a shoulder disposed in spaced relation to each of said notches respectively, collars slidably fitted upon said end members respectively and engaging in said rabbets and abutting against said shoulders of the said bars so as to overlie the ends of the bars to thereby releasably retain the bars in interfitting relation with the end members, said bars having notches intermediate their opposite ends extending inwardly from their inner edges, a band disposed in said last mentioned notches to thereby releasably retain said bars in circumferential spaced relation and threaded coupling members threadedly engaging over the outer ends of said end members for retaining said collars in position on said end members respectively and providing means for coupling the well screen in a pipe line.

2. In a well screen, oppositely disposed threaded tubular end members each having an annular groove in its outer face adjacent the inner end thereof providing an annular bead extending from said groove to the inner end of the end member, bars with inwardly converging side walls and having notches adjacent their opposite ends opening through their inner edges and receiving therein the annular beads of said end members respectively with the extremities of said bars interfitting in said annular grooves to thereby dispose said bars in longitudinally extending relation between and interconnected with said end members, said bars having their opposite ends externally rabbeted providing a shoulder disposed in spaced relation to each of said notches respectively, collars slidably fitted upon said end members respectively and engaging in said rabbets and abutting against said shoulders of said bars so as to overlie the extremities of said bars to thereby releasably retain the bars in interfitting relation with the end members, each of said bars having a notch intermediate the said end members, a band fitted in said notches and hav-

ing projections disposed between the bars to thereby releasably retain the bars in circumferential spaced relation and threaded coupling members threadedly engaging over the outer ends of said end members for retaining said collars in position against the shoulders of said bars and providing means for coupling the well screen in a pipe line.

3. In a well screen, oppositely disposed threaded tubular end members each having an annular groove in its outer face adjacent the inner end thereof and providing an annular bead extending from said groove to the inner end of the end member, longitudinally extending bars having notches adjacent their opposite ends extending inwardly from their inner edges and receiving therein the annular beads of said end members respectively with the extremities of said bars interfitting in said annular grooves to thereby dispose said bars in longitudinally extending relation between and interconnected with said end members, collars fitted upon said end members respectively and overlying the extremities of said bars to thereby retain the bars in interfitting relation with the end members and threaded coupling members engaging over the outer ends of said end members respectively for retaining the collars in position and providing means for coupling the well screen in a pipe line.

4. In a well screen, oppositely disposed threaded tubular end members each having an annular groove in its outer face adjacent the inner end thereof and providing an annular bead extending from said groove to the inner end of the end member, bars having notches adjacent their opposite ends extending inwardly from their inner edges in which are received the annular beads of said end members respectively with the extremities of said bars interfitting in said annular grooves to thereby dispose said bars in longitudinally extending relation between and interconnected with said end members, collars fitted upon said end members respectively and overlying the extremities of said bars to thereby retain the bars in interfitting relation with the end members, means interconnected with said bars intermediate the end members for securing said bars in circumferential spaced relation and threaded coupling members engaging over the outer ends of said end members for retaining the collars in position and providing means for coupling the well screen in a pipe line.

5. In a well screen, oppositely disposed threaded tubular members each having an annular groove in its outer face adjacent the inner end thereof and providing an annular bead extending from said groove to the inner end of said tubular member, bars having notches adjacent their opposite ends extending inwardly from their inner edges and in which are received the annular beads of said tubular members respectively with the extremities of said bars interfitting in said annular grooves to thereby dispose said bars in longitudinally extending relation between and interconnected with said tubular members, collars fitted upon said tubular members respectively and overlying the extremities of said bars to thereby retain the bars in interfitting relation with the tubular members and means engaging with the tubular members for retaining the collars against relative movement away from the bars.
